Original application June 9, 1937, Serial No.
147,178. Divided and this application July 31,
1940, Serial No. 348,904

12 Claims. (Cl. 103—162)

The present invention relates to improvements in hydraulic pumps, and particularly to a new and improved pump adapted for high speed and pressure operation.

One object of the invention is to provide a novel hydraulic pump which is silent in operation at high pressures, and in which the mechanical reaction of the hydraulic pressure on the wearing surfaces is hydraulically balanced.

Another object is to provide a new and improved pump valve which will not deflect under high pressures, and which is constructed to prevent sudden pressure changes in the pump cylinders with resultant pressure surges in the delivery.

Further objects and advantages will become apparent as the description proceeds.

In the accompanying drawings,

Figure 1 is an axial sectional view, taken along line 1—1 of Fig. 2, of a pump embodying the features of our invention.

Fig. 2 is an end elevational view of the pump.

Fig. 3 is a fragmentary sectional view of the pump valve taken along line 3—3 of Fig. 1.

Fig. 4 is a fragmentary transverse sectional view taken substantially along line 4—4 of Fig. 1, and showing the face of the stationary valve member.

Fig. 5 is a fragmentary transverse sectional view taken substantially along line 5—5 of Fig. 1, and showing the face of the movable valve member.

Fig. 6 is a sectional detail view taken along line 6—6 of Fig. 4.

Fig. 7 is an enlarged fragmentary sectional view of one of the pump pistons.

While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative constructions falling within the spirit and scope of the invention as expressed in the appended claims.

The present application is a division of our copending application Serial No. 147,178, filed June 9, 1937.

Referring more particularly to the drawings, the hydraulic pump, constituting the exemplary embodiment of the invention, comprises a closed pump housing 13 which may be of any suitable form or construction, and which in the present instance is generally rectangular in shape, and

has a bottom wall 14 adapted to be bolted or otherwise secured to a suitable support (not shown). The housing 13 also has opposite end walls 15 and 16, and is closed at the top by a removable cover plate 17.

A suitable drive shaft 18 extends longitudinally through the housing 13, and is journaled at opposite ends in the walls 15 and 16. Integral with the wall 15 is a large external circular boss 19 having an axial bore 20 counterbored at the inner end. A stationary valve plug 21, in the form of a single cylindrical block, is tightly pressed into the bore 20, and is located axially by a peripheral end flange 22 seated in the counterbore. To locate the plug 21 angularly, it is formed with a longitudinal groove 23 engaging a pin 24 on the inner end of a screw 25 threaded radially into the boss 19. Formed in the plug 21 is an axial bore 26 which is closed at the outer end, and which is open and flared at the inner end. A bushing 27 is fitted in the bore 26, and supports one end of the shaft 18.

The opposite end wall 16 is formed with a bore 28 in axial alignment with the bushing 27. Preferably, an antifriction bearing 29 is mounted in the bore 28 to support the shaft 18 which extends therefrom externally of the housing 13 for connection to a suitable source of power (not shown). To prevent the entry of air, dust and other foreign matter through the bearing 29 into the housing 13, an oil seal 30 is mounted in the outer end of the bore 28, and is held in place by an end plate 31 bolted to the outside of the wall 16.

Secured to the shaft 18 for rotation therewith is a cylinder block or body 32. In the present instance, the body 32 is formed with an axial bore 33 slidably receiving the shaft 18, and is located axially thereon by abutment against a shaft enlargement 34. The end of the enlargement 34 is flattened on opposite sides to define a key 35 which interfits separably with a diametrical notch 36 in the adjacent end of the body 32. Preferably, the root of the notch 36 and the end face of the key 35 are arcuate in shape to provide simple machining.

The body 32 is in the form of a spool having a peripheral cylinder flange 37 and an axially spaced guide flange 38, and defining an intermediate spring space 39. A plurality of parallel bores 40, six in the present instance, open through the flange 37, and constitute pump cylinders annularly arranged in uniformly spaced relation about the shaft 18. Similarly, the flange 38 is formed with guide bores 41 in axial alignment

with the bores or cylinders 40. Rigidly secured as by means of bolts 42 to the outer end face of the flange 37 and coextensive in diameter therewith is a circular valve plate 43 which closes the pressure ends of the cylinders 40, and which preferably is formed with circular recesses defining slightly enlarged closed end extensions of the cylinders.

A plurality of pump plungers or pistons 44 are reciprocably disposed respectively in the open ends of the cylinders 40 and are slidably guided at their outer ends in the bores 41. The pistons 44 are urged outwardly on their suction or intake strokes by individual compression springs 45 located within the annular space 39. Each of the springs 45 seats at one end against a ring retainer 46 positioned against the flange 37, and at the other end against a key retainer 47 engaging a peripheral groove 48 in the associated piston 44.

The pistons 44 are operable in uniformly timed sequence, with a variable stroke as hereinafter described, by a swash or cam plate 49 which is journaled on a pin 50 for angular or rocking adjustment into different inclined positions. The pin 50 is pressed in spaced lugs 51 in the housing 13 and is perpendicular to the axis of the shaft 18. The plate 49 has a flat annular cam face 52 which freely encircles the shaft enlargement 34 and which is engaged by floating shoes 53 operatively connected to the outer ends of the pistons 44.

Each of the shoes 53 is in the form of a disk having a flat annular bearing face 54 of ample size in sliding engagement with the cam face 52, and having a hollow central spherical projection 55 seating for universal movement in a complementary socket 56 in the outer end of the associated piston 44. A retainer 57 is loosely fitted in the outer end of an axial bore 58 in the piston 44, and is secured therein by a transverse lock pin or rivet 59. The retainer 57 has a semispherical head 60 which engages the interior of the projection 55 to confine the shoe 53 adjustably in the socket 56, and which is connected by a reduced stem 61 extending freely through a central opening 62 in the projection.

The bore 58 opens at the inner end through a small aperture 63 to the cylinder 40, and hence provides for a longitudinal pressure passage permitting the flow of lubricant to the bearing surfaces of the shoe 53. As one factor affecting quietness in pump operation, the lubricant passage should be small. Since it is impracticable to drill the long bore 58 sufficiently small in hard metal, such as the piston material, a seamless tube 64 is tightly fitted therein between the retainer 57 and the aperture 63, and defines the actual pressure passage. Fluid or oil from the closed end of the cylinder 40 passes through the aperture 63, the tube 64 and about the retainer 57 to the bearing surfaces of the socket 56 and ball projection 55. Fluid or oil also passes through the opening 62 to the bearing surfaces between the plate 49 and the shoe 53.

The bearing surfaces between the plate 49 and the shoe 53 and between the projection 55 and the socket 56 are closely lapped to provide a hydraulic seal, and are hydraulically balanced against the mechanical reaction on the piston to the hydraulic pressure in the cylinder 40, so as to maintain at all times good bearing engagement with a proper lubricating film. The bearing face 54 of the shoe 53 is relieved at the inner edge by an annular notch 65, and is formed with

a concentric drain groove 66 relieved through a plurality of drain apertures 67. The central portion of the bearing face 54, circumscribed by the inner edge of the groove 66, is under pressure, 5 and is substantially equal in area to the pressure end of the piston 44 so as to counterbalance the outward thrust of the hydraulic pressure in the cylinder 40. The pressure area of the face 54 may be equal to the piston end area, but preferably is slightly larger to balance part of the outward pressure of the spring 45. Since the groove 66 prevents outward spreading of the pressure film, the full wearing surface of the face 54 10 can be much larger than the pressure balanced area without interfering at any time with good bearing contact. The effective pressure area of the socket 56 is somewhat less by reason of the opening 62 than that of the piston 44, but is sufficiently large to obtain substantially a hydraulic 15 balance, the lubricating film being maintained 20 under a slight excess pressure to assure good bearing contact.

The valve stator 21 and the plate 43 have annular end faces 68 and 69 in bearing engagement, 25 and constitute a rotary end face valve for controlling the admission and discharge of fluid respectively to and from the pump units. Since the stator 21 is in the form of a heavy plug mounted in the large boss 19, the stationary valve 30 face 68 is not subject to deflection under heavy pressure.

The valve stator 21 (see Fig. 4) is provided with two arcuate suction and delivery ports 70 and 71 separated by diametrically spaced land 35 areas 72 and 73 and arranged in concentric relation to the shaft 18. These ports are located at opposite sides of an axial plane intersecting the land areas and perpendicular to the pivotal axis of the swash plate 49. Formed in the valve 40 face 69 of the plate 43 are a plurality of ports 74 which open respectively to the closed ends of the pump cylinders 40, and which are annularly arranged in a circle of the same curvature as the ports 70 and 71 for movement successively 45 across the latter upon rotation of the cylinder body 32. The ports 70, 71 and 74 are offset from the centers of the cylinders 40, and preferably 50 are located at the innermost side areas thereof adjacent the shaft 18. As a result, the contacting areas of the valve faces 68 and 69 can be made 55 small to lessen the likelihood of manufacturing errors or irregularities and the chance of valve leakage, and are located closely to the center of rotation to reduce the peripheral speed. Also, any air collecting in the cylinders 40 will be separated from the liquid by centrifugal force, and pass out with the pump delivery.

The valve faces 68 and 69 are hydraulically balanced against the pressure in the minimum 60 number of cylinders 40 on the pressure side of the pump to maintain a proper oil film and good contact. Since the cylinders under pressure are alternately two and three, the area of the valve face 68 on the pressure side, including the port 71, is made substantially equal to the aggregate 65 area of the ends of two pistons 44. To obtain a bearing surface larger than the balancing pressure area, an annular concentric drain groove 75 is formed in the face 68 about the ports 70 and 71 to prevent spreading of the pressure film, and is relieved at spaced points to the periphery of the plug 21. The inner peripheral edge of the valve face 68 is relieved to the bore 26, and the liquid draining from the valve faces into the bore 70 serves to lubricate the bushing 27. Liquid col-

lecting in the bore 26 at opposite ends of the bushing 27 is free to pass through drain holes 76 and 77 to the locating spline groove 23, and from there into the housing 13. Liquid collecting in the housing 13 is free to return through a passage 78 to the pump inlet. If the pump is mounted above the level of the source of liquid supply, the passage 78 may be closed, and the housing 13 may be drained through a bottom opening 79 connected to the source.

It will be evident that when the swash plate 49 is angularly disposed, rotation of the cylinder body 32 will cause the pistons 44 to be reciprocated in timed sequence and with a simple harmonic motion, and that each piston will be moving through its suction and pressure strokes while the associated cylinder 40 is in communication respectively with the inlet and delivery ports 70 and 71. As the pistons 44 of each set of diametrically opposed pistons reach top and bottom dead centers respectively, the associated cylinders 40 will be closed by the land areas 72 and 73, and at these times only two cylinders will be open to either of the valve ports 70 and 71. At all other times, three cylinders 40 will be open to each of the valve ports 70 and 71. Consequently, the pump will discharge continuously, and the rate of discharge is substantially constant for any given setting of the swash plate 49. If the angular position of the swash plate 49 is changed, the length of the piston stroke will be adjusted to adjust the rate and volume of pump delivery. When the plate 49 is adjusted into a plane perpendicular to the shaft 18, no reciprocation will be imparted to the pistons 44.

Preferably, the suction and delivery ports 70 and 71 are angularly advanced in relation to the top and bottom dead center positions of the pistons 44 so as to effect a pressure equalization in each cylinder 40 just before the start of both the pressure and suction strokes. Each of the cylinder ports 74 will be closed by the land area 72 during the initial part of the pressure stroke to cause the pressure therein to be built up approximately to the pump delivery pressure before free communication with the port 71. Similarly, each port 74 will be closed by the land area 73 during the initial part of the suction stroke so that the pressure will be expanded approximately to the suction pressure effective in the port 70 before free communication therewith.

To permit such pressure equalization, the land areas 72 and 73 are somewhat wider than the ports 74 so that each cylinder 40 is closed over a predetermined degree of revolution. For fixed operating conditions and upon making proper allowance for leakage past the valve faces and pistons, the angular advance of the ports 70 and 71 may be accurately calculated to obtain a quietly operating pump. However, the operating conditions are subject to variations, such, for example, as changes in delivery pressure, speed, displacement, temperature influences and the kind and condition of the fluid being handled. These changes influence the pump leakage and the pressure gradients. The valve ports 70 and 71 are therefore advanced to time the opening of the cylinder ports 74 for average or mean operating conditions.

Means may be provided for graduating even the small pressure changes which will be present when the variable pressures in the effective range deviate from the mean operating pressure. This means consists of short restricted bleed grooves 80 in the valve face 68 (see Figs. 4 and 6) open-

ing to and constituting extensions of the ends of the arcuate ports 70 and 71. The grooves are so graduated that the cylinder ports 74 will not open abruptly to the ports 70 and 71, thereby avoiding sudden shock even if the cylinder pressure is not equalized with that of the stationary port with which it is about to communicate.

The gradual pressure changes in passing from either to the other of the ports 70 and 71 also have the important function of preventing the piston shoes 53 from clicking. During movement through the intake zone, each shoe 53 is held against the cam plate 49 with a light initial pressure determined by the spring 45. In the pressure zone, the spring pressure is supplemented by the hydraulic pressure acting through the piston 44 so that the oil film between the cam plate 49 and the shoe 53 and between the latter and the piston is compressed under a heavy pressure. By reason of the advance of the ports 70 and 71 and/or the provision of the bleed grooves 80, the pressure on the film is alternately gradually relieved and applied, thereby placing the shoe 53 in substantial balance before each port opening. Sudden pressure surges tending to effect separation of the shoe 53 from the cam plate 49 at transition points in the operation are consequently avoided.

As noted, one of the features of the present pump is quietness in operation. The hydraulic balance of the piston shoes 53 and the valve 68, 69 against the mechanical reaction of the hydraulic pressure contributes to this result. The elimination of pressure surges or impulses, by reason of the angular advance of the ports 70 and 71 and the provision of the bleed grooves 80, also reduces noise in operation. As another important factor in avoiding noise, the volume of pressure liquid in the closed ends of the cylinders 40 at the end of the pressure stroke is held to a minimum. To this end, the piston clearance in the valve plate 43 is made as small as is practically convenient, and the pressure passages through the pistons 44 are reduced in size by means of the tubes 64. Also, the pivot pin 50 is located at a point adjacent the axis of each piston 44 as the latter moves into top dead center position at the end of the pressure stroke. As a result, the inward limit of movement of the pistons 44 is substantially constant and close to the inner ends of the cylinders 40, while the outward limit of movement is variable in accordance with changes in the angular position of the swash plate 49.

The inlet port 70 may be connected in any suitable manner to the source of liquid supply, and in the present instance is in communication at the bottom or root with a plurality of longitudinal bores 81 in the valve plug 21. The outer ends of the bores 81 are intersected by a recess 82 formed in the periphery of the plug, and registering with a passage 83 opening through the peripheral wall of the boss 19. A line 84 connects the passage 83 with a source of supply, such as a sump or reservoir 85. The delivery port 71 is in communication at the bottom or root with a plurality of longitudinal bores 86 formed in the plug 21. A recess 87 in the periphery of the plug 21 intersects the bores 86, and is in registration with an outlet passage 88 opening through the boss 19 and connected to a pressure line 89.

The swivel plate 49 may be angularly adjusted about the pin 50 to vary the output of the pump. Within the broad aspects of the present invention,

such adjustment may be effected by any suitable means. In the present instance, the swivel plate 49 is automatically controlled in response to a predetermined control pressure. Thus, the plate 49 is automatically adjusted to reduce the pump delivery upon an increase in the control pressure, and to increase the delivery upon a decrease in the pressure. The means for this purpose comprises a control piston 90 acting on the free end of the swash plate 49 in a direction to level off the latter against the hydraulic reaction in the cylinders 40 and the action of the piston return springs 45. The control piston 90 is reciprocable in a cylinder 91 opening through the wall 16, and closed at the outer end by the cover or stop plate 31. The cylinder 91 extends parallel to the shaft 18, and preferably is located diametrically opposite the pin 50 and outside the circle of revolution of the cylinders 40 so that the thrust of the piston 90 against the plate 49 will have a moment arm considerably longer than that of the aggregate opposing forces resulting from the hydraulic reaction through the pistons 44. The diameter of the piston 90 and the moment arm of the force exerted thereby determine the pressure required in the cylinder 91 in relation to the pump delivery pressure to balance the cam or swash plate 49. By providing a comparatively large diameter and a relatively long moment arm as shown, the balancing pressure required in the cylinder 91 will be lower than the corresponding pump delivery pressure.

The control piston 90 is operatively connected to the swash plate 49 by a pin 92. One end of the pin 92 is formed with a spherical head 93 seated for universal pivotal movement in a complementary socket 94 in the free end of the plate 49, and the other end is rounded and seated in a complementary socket 95 in the end wall of the piston 90. A coiled compression spring 96 acts to maintain the head 93 within the socket 94.

Fluid under pressure is adapted to be supplied to or exhausted from the inner end of the cylinder 91 to adjust the swash plate 49. In the present instance, the supply of fluid is controlled by a metering valve 97 which preferably is built into the cover 17 and which is automatically responsive to the aforesaid control pressure. The details of the valve 97 and the source of the aforesaid control pressure form no part of the present invention and are therefore not specifically illustrated herein but are disclosed in our aforesaid copending application.

We claim as our invention:

1. A hydraulic pump comprising, in combination, a casing having a wall with inlet passage means and pressure delivery passage means, an external boss integral with said wall and formed with a bore opening therethrough to the interior of said casing, a cylindrical plug tightly fitted in said bore and having an inner end flange engaging the inside of said wall, spline means for locating said plug angularly of said bore, the inner end of said plug defining a flat stationary valve face with arcuate intake and delivery ports in communication through said plug respectively with said passage means, an axial bore in said plug centrally of said ports and draining from opposite ends to the interior of said casing, a drive shaft in said casing and journaled at one end in said last mentioned bore, a pump body fixed to said shaft and having a plurality of parallel pump cylinders annularly arranged about said shaft, a valve face on one end of said body having ports opening respectively to the closed

ends of said cylinders, and contacting with said stationary valve face for movement of said cylinder ports successively across said intake and delivery ports, a plurality of pistons reciprocable in said cylinders, and means for effecting reciprocation of said pistons in timed sequence, said plug being of sufficient mass to prevent deflection of said stationary valve face under pump pressure.

10. 2. A hydraulic pump comprising, in combination, a casing having a bore in one wall, a unitary plug of substantial mass tightly fixed in said bore and defining a stationary valve face at the inner end, a drive shaft in said casing, a pump body

15 fixed on said shaft and having a plurality of parallel pump cylinders annularly arranged about the axis of rotation, a valve face on one end of said body and contacting with said stationary valve face, a plurality of pistons reciprocable in said cylinders, and means for effecting reciprocation of said pistons in timed sequence, said mass being sufficient to prevent appreciable deflection of said stationary valve face under pump pressure.

20 3. A hydraulic pump comprising, in combination, a pump casing having fluid inlet passage means and pressure delivery passage means, a shaft journaled in said casing, a pump body secured to said shaft for rotation and having a plurality of parallel cylinders annularly arranged about said shaft, a plurality of pistons reciprocable in said cylinders, valve means for connecting said cylinders alternately and successively to said inlet and delivery passage means respectively

25 during the intake and pressure strokes of said pistons, a swash plate mounted in said casing for reciprocating said pistons in timed sequence upon rotation of said body, said swash plate having a flat bearing face, each piston having a floating shoe at the outer end with a bearing face slidably engaging said flat bearing face of said swash plate and being hydraulically balanced against the mechanical reaction of the pressure in the associated cylinder.

30 4. A hydraulic pump comprising, in combination, a casing having fluid inlet passage means and pressure delivery passage means, a shaft journaled in said casing, a pump body rotatable with said shaft and having a plurality of parallel cylinders annularly arranged about said shaft and having a plurality of guide bores in axial alignment with said cylinders, a plurality of pistons reciprocable in said cylinders and said

35 guide bores, valve means for connecting said cylinders alternately and successively to said inlet and delivery passage means respectively during the intake and pressure strokes of said pistons, a swash plate adapted to be mounted in inclined position relative to a perpendicular to said shaft for reciprocating said pistons in timed sequence, and individual compression springs encircling said pistons between said cylinders and guide bores and urging said pistons outwardly into operative engagement with said swash plate.

40 5. A hydraulic pump comprising, in combination, a pump casing having fluid inlet passage means and pressure delivery passage means, a rotatable pump body having a plurality of parallel cylinders annularly arranged about the axis of rotation, a plurality of pistons reciprocable in said cylinders, means for effecting reciprocation of said pistons in timed sequence, and valve means for connecting said cylinders alternately and successively to said inlet and delivery passage means, said valve means comprising a sta-

tionary annular valve face with arcuate inlet and delivery ports separated by land areas at the ends, and with an annular groove outside of said ports and relieved to the atmosphere to define a circumscribed pressure film area less than the valve face area and substantially equal on the pressure side of the pump including said delivery port to the aggregate area of the minimum number of cylinders adapted to be under pressure at one time.

6. A hydraulic pump comprising, in combination, a pump casing having fluid inlet passage means and pressure delivery passage means, a pump body having a plurality of parallel annularly arranged cylinders, a plurality of pistons reciprocable in said cylinders, means for effecting reciprocation of said pistons in timed sequence, and end face valve means for connecting said cylinders alternately and successively to said inlet and delivery passage means, said valve means comprising contacting valve faces having means for defining a pressure film area substantially equal on the pressure side of the pump to the aggregate area of the minimum number of cylinders adapted to be under pressure at one time.

7. A hydraulic pump comprising, in combination, a pump casing having fluid inlet passage means and pressure delivery passage means, a rotatable pump body having a plurality of parallel cylinders annularly arranged about the axis of rotation, a plurality of pistons reciprocable in said cylinders, means for effecting reciprocation of said pistons in timed sequence, and valve means for connecting said cylinders alternately and successively to said inlet and delivery passage means, said valve means comprising a stationary valve face, and means in said face defining a pressure film area of a size adapted substantially to balance hydraulically the mechanical reaction of the hydraulic pressure on said valve means while maintaining a hydraulic seal.

8. In a hydraulic pump, in combination, a pump body having a cylinder, a piston reciprocable in said cylinder, an inclined swash plate operatively engaging the outer end of said cylinder, means for effecting relative rotation between said body and said swash plate, valve means for admitting fluid to said cylinder and delivering pressure fluid therefrom respectively during the intake and delivery strokes of said piston, said piston being formed with an axial bore opening through a restricted aperture to said cylinder, a tube fitted into said bore to reduce the size of the passage therethrough, a spherical socket in the outer end of said piston, a shoe having a flat annular bearing face in slidable engagement with said swash plate and having a central rounded projection seating for universal adjustment in said socket, a retainer loosely secured in the outer end of said bore and having a head coacting with the inside of said projection for confining said shoe in engagement with said socket, whereby fluid from said cylinder passing through said aperture and said tube is available to lubricate the contact surfaces between said socket and projection and between said swash plate and shoe, an annular groove formed in the bearing face of said shoe and relieved to the atmosphere to define a circumscribed pressure area less than the total area of said bearing face and approximately equal to the end area of said piston to effect a hydraulic balance of said shoe against the mechanical reaction to the pressure in said cylinder.

9. In a hydraulic pump, in combination, a pump body having a cylinder, a piston reciprocable in said cylinder, an inclined swash plate having a flat bearing face operatively engaging the outer end of said piston, means for effecting relative rotation between said body and said swash plate, valve means for admitting fluid to said cylinder and delivering pressure fluid therefrom respectively during the intake and delivery strokes of

10 said piston, said piston being formed with a bearing socket in the outer end and with a longitudinal passage opening from said cylinder to said socket, a shoe having a flat annular bearing face in slidable engagement with said bearing face of said swash plate and having a central projection seating for angular adjustment in said socket, and an opening in said shoe for connecting said passage to said bearing face.

10. In a hydraulic pump, in combination, a pump body having a cylinder, a piston reciprocable in said cylinder, an inclined swash plate operatively engaging the outer end of said cylinder, means for effecting relative rotation between said body and said swash plate, valve means for admitting fluid to said cylinder and delivering pressure fluid therefrom respectively during the intake and delivery strokes of said piston, said piston being formed with a bearing socket in the outer end and with a longitudinal passage opening from said cylinder to said socket, a shoe having a flat bearing face in slidable engagement with said swash plate and having a central projection seating for angular adjustment in said socket, and an opening in said shoe for connecting said passage to said bearing face.

20 25 30 35 40 45 50 55 60 65 70 75

11. In a hydraulic pump, in combination, a pump body having a cylinder, a piston reciprocable in said cylinder, an inclined swash plate operatively engaging the outer end of said cylinder, means for effecting relative rotation between said body and said swash plate, valve means for admitting fluid to said cylinder and delivering pressure fluid therefrom respectively during the intake and delivery strokes of said piston, said piston being formed with a bearing socket in the outer end and with a longitudinal passage opening from said cylinder to said socket, a shoe having a flat bearing face in slidable engagement with said swash plate and having a central projection seating for angular adjustment in said socket, and an opening in said shoe for connecting said passage to said bearing face, said bearing face being formed to maintain a lubricating pressure film area to balance substantially the mechanical reaction to the pressure in said cylinder.

11. In a hydraulic pump, in combination, a pump body having a cylinder, a piston reciprocable in said cylinder, an inclined swash plate operatively engaging the outer end of said cylinder, means for effecting relative rotation between said body and said swash plate, valve means for admitting fluid to said cylinder and delivering pressure fluid therefrom respectively during the intake and delivery strokes of said piston, said piston being formed with a bearing socket in the outer end and with a longitudinal passage opening from said cylinder to said socket, a shoe having a flat bearing face in slidable engagement with said swash plate and having a central projection seating for angular adjustment in said socket, and an opening in said shoe for connecting said passage to said bearing face, an annular relieved groove formed in said bearing face to define a pressure area less than the total area of said bearing face and approximately equal to the end area of said piston to effect a hydraulic balance of said shoe against the mechanical reaction to the pressure in said cylinder while maintaining bearing engagement with said plate.

12. A hydraulic pump comprising, in combination, a casing having a wall with inlet passage means and pressure delivery passage means, an external boss integral with said wall and formed with a bore opening to the interior of said casing, a cylindrical plug tightly fitted in said bore and having an inner end flange engaging the inside of said wall, spline means for locating said plug angularly of said bore, the inner end of said plug defining a flat stationary valve face with arcuate intake and delivery ports in communication through said plug respectively with said passage means, an axial bore in said plug centrally of

said ports, a drive shaft in said casing and journaled at one end in said last mentioned bore, a pump body fixed to said shaft and having a plurality of parallel pump cylinders annularly arranged about said shaft, a valve face on one end of said body having ports opening respectively to the closed ends of said cylinders, and contacting with said stationary valve face for movement of said cylinder ports successively across said intake

5 and delivery ports, a plurality of pistons reciprocable in said cylinders, and means for effecting reciprocation of said pistons in timed sequence, said plug being of sufficient mass to prevent deflection of said stationary valve face under pump pressure.
